UNITED STATES PATENT OFFICE.

WILLARD T. CHILDS, OF SPRINGFIELD, MASSACHUSETTS.

STREET-CAR ADVERTISING-SIGN.

1,031,169.

Specification of Letters Patent.

Patented July 2, 1912.

Application filed November 2, 1911. Serial No. 658,239.

To all whom it may concern:

Be it known that I, WILLARD T. CHILDS, a citizen of the United States, residing at Springfield, in the county of Hampden and 5 State of Massachusetts, have invented certain new and useful Improvements in Street-Car Advertising-Signs, of which the following is a specification.

The present invention relates to certain 10 new and useful improvements in the construction of illuminated signs such as are adapted to be applied to street cars for the use of indicating the designation thereof, or to motor vehicles to indicate the number of 15 the license or any other desired matter.

The object of the invention is to provide 20 a sign of this character which is simple and inexpensive in its construction, which can be readily mounted upon a street car or the like, and which is peculiarly constructed to admit of the display words or characters being 25 readily changed as may be desired.

A further object of the invention is to 30 provide an illuminated sign in which the characters or words will be very distinctly displayed either during the day or after 35 dark, which is compact in its construction, and which can be easily and quickly mounted in position or removed therefrom.

With these and other objects in view, the 40 invention consists in certain novel combinations and arrangements of the parts as will more fully appear as the description proceeds, the novel features thereof being 45 pointed out in the appended claims.

For a full understanding of the invention, reference is to be had to the following 50 description and accompanying drawings, in which:

Figure 1 is a front elevation of an illuminated sign constructed in accordance with the invention. Fig. 2 is a perspective view of the main frame of the illuminated sign, the electric light bulbs and display plates 55 being removed. Fig. 3 is a horizontal sectional view through the device on the line 3—3 of Fig. 1. Fig. 4 is a front elevation of the sign with the display plates removed, portions of the frame being broken away 60 and shown in section. Fig. 5 is an enlarged sectional view through one of the forward corners of the main frame and a portion of one of the advertising or display plates, the 65 said view bringing out certain details of the fastening means utilized for holding the display plates in position. Fig. 6 is a front

elevation of an advertising or display plate, the said view showing a modification in which various individual letters are adapted to be applied to the plate so as to spell any 60 desired word. Fig. 7 is a front elevation of a portion of an illuminated sign, showing a further modification of the invention. Fig. 8 is a horizontal sectional view through the same on the line 8—8 of Fig. 7. Fig. 9 is a 65 front elevation of one end of one of the display or advertising plates, and Fig. 10 is a detail sectional view on the line 10—10 of Fig. 7.

Corresponding and like parts are referred 70 to in the following description and indicated in all the views of the drawings by the same reference characters.

The supporting frame upon which the 75 sign plates are mounted may be conveniently formed from a single piece of sheet material, as indicated upon the drawings, and comprises a back 1 provided at the upper end thereof with a pair of hook members 2 adapted to be placed in engagement 80 with some suitable support such as that indicated at 3. A side member 4 extends forwardly from each side of the base 1, the outer edge of each of the side members being formed with an inwardly extending 85 flange 5. Each of the side members or walls 4 is provided upon the inner face thereof with a series of electric light sockets 6 adapted to support suitable incandescent lights 7. These lights are preferably of the 90 elongated type and project inwardly in a substantially parallel relation to the back 1. Suitable wires 8 are utilized for supplying current to the electric lights, and these wires would be connected to some suitable plug 95 adapted to be applied to a convenient socket upon the street car so as to provide for the lighting of the lamps when the sign is in use.

The front of the frame is formed by a series 100 of removable plates 9 which have suitable characters 10 punched therethrough. These plates are provided at opposite ends thereof with inverted key hole slots 11 adapted to be engaged by headed studs 12 projecting 105 from the respective flanges 5. The heads of the studs pass readily through the enlarged ends of the key hole openings, and the plates are then moved downwardly to bring the shanks of the studs within the contracted upper ends of the key hole openings. The 110 plate is thereby held securely against out-

ward displacement, and rubber washers 13 are applied to the shanks of the headed studs so as to hold the plates yieldingly against the flanges 5 and prevent rattling or 5 accidental displacement thereof. The characters 10 which are punched through the plates may form words suitable for conveying any desired information, or may form designs or figures suitable for advertising 10 or display purposes. The back 1 would be painted white so that the characters 10 would be very distinct during the day, and at night the lamps 7 would be lit so as to illuminate the perforations 10 and render 15 the same easily visible at comparatively great distances.

A modification is shown in Fig. 6 in which a sign plate 9^a is provided with a series of openings 14 adapted to have 20 smaller plates 15 applied thereto, the said smaller plates having individual letters or characters 16 punched therein. Each of these smaller plates 15 is provided with a pair of upwardly and downwardly projecting 25 ears 17 having inverted key hole slots 18 therein, the said key holes adapted to engage the headed studs 19 to retain the individual plates removably in position. Each of the individual plates 15 is provided with 30 an individual letter or character 16, and the said individual plates can be assembled in any desired manner so as to spell certain words. The different sign plates 9^a would be applied to the headed studs 12 in the same 35 manner as the plates 9, the inverted key hole slots 11 being provided in the plates for that purpose.

A further modification is shown in Figs. 7, 8, 9 and 10, in which positive means is 40 provided for locking the plates against accidental displacement. The construction of the supporting frame is the same as that previously described, and the headed studs 12 project from the flanges 5 in the same 45 manner. The display plates 9^b are provided with suitable perforate characters 20 adapted to be brought out and rendered distinct either by the illuminated lights 12 or the white background formed by the rear 50 plate 1. Opposite ends of the plates 9^b are provided with the inverted key hole slots 21 having lateral extensions 22 at the upper ends thereof. The display plates 9^b are applied to the headed studs as previously 55 described, and then shifted laterally to bring the shanks of the headed studs into the lateral extensions 22 of the inverted key hole slots 21. A spring catch 23 upon one 60 end of the plate 9^b then springs into engagement with the edge of one of the flanges 5

so as to hold the plate against longitudinal movement. The plate is thereby held securely against displacement, and it is impossible to remove the plate until after the spring catch 23 has been disengaged from 65 the flange 5 to admit of the plate being shifted longitudinally to bring the shank of the headed stud into the vertical portion of the key hole slot. The nose of the catch 23 is provided with an arm projecting forwardly 70 through an opening in the plate and terminating in a finger piece 24. When it is desired to move the plate, it is merely necessary to pull outwardly upon the finger piece 24 so as to disengage the catch 23 from the 75 flange 5, and then to shift the plate first longitudinally and then upwardly, as previously described.

From the foregoing description, it will be obvious that I have provided an illuminated 80 sign which is simple and inexpensive in its construction and which admits of the display matter being easily and quickly changed as may be found necessary.

Having thus described the invention, 85 what I claim as new and desire to secure by Letters Patent, is:—

1. An illuminated sign including a casing having an open side, a lamp within the casing, headed studs projecting from the casing on opposite sides of the open side thereof, rubber washers upon the headed studs, and display plates applied to the open side of the casing and having characters punched therein, the said display plates being formed 95 with key hole slots adapted to interlock with the headed studs and the rubber washers serving to prevent rattling of the display plates.

2. An illuminated sign including a casing 100 formed of a single piece of sheet material and comprising a back having opposite edges thereof extended outwardly to provide sides and the said sides being provided with inwardly extending flanges, electric 105 light sockets applied to the sides, headed studs projecting from the inwardly projecting flanges of the sides, and a series of plates connecting the flanges of the sides and 110 forming the front of the casing, the said plates having characters punched therein and being formed with key hole slots adapted to interlock with the headed studs.

In testimony whereof I affix my signature 115 in presence of two witnesses.

WILLARD T. CHILDS.
